(57) CLAIM

The ornamental design for a combined decorative scarf and tee shirt holder, as shown and described.

DESCRIPTION

FIG. 1 is a front top perspective view of a combined decorative scarf and tee shirt holder showing my new design;

FIG. 2 is a side view thereof;

FIG. 3 is a top view thereof;

FIG. 4 is a bottom view thereof; and,

FIG. 5 is a perspective view of the decorative scarf and tee shirt holder as worn by a user thereof.

The broken lines showing of a female form in FIG. 5 is for illustrative purposes and forms no part of the claimed design.
